CLAIM

The ornamental design for a vehicle seat, as shown and described.

DESCRIPTION

FIG. 1 is a front, right side perspective view of a vehicle seat;

FIG. 2 is a front view of the vehicle seat;

FIG. 3 is a rear view of the vehicle seat;

FIG. 4 is a top view of the vehicle seat;

FIG. 5 is a bottom view of the vehicle seat; and,

FIG. 6 is a right side view of the vehicle seat.

In the drawings, the left side view of the vehicle seat is omitted because it is identical to the right side view of the vehicle seat.
